UNITED STATES PATENT OFFICE.

WESLEY G. NICHOLS, OF CHICAGO HEIGHTS, ILLINOIS, ASSIGNOR TO AMERICAN MANGANESE STEEL COMPANY, OF CHICAGO, ILLINOIS, A CORPORATION OF MAINE.

OPEN-SLOT RAILWAY CROSSING.

Application filed December 17, 1924. Serial No. 756,377.

To all whom it may concern:

Be it known that I, WESLEY G. NICHOLS, a citizen of the United States, residing at Chicago Heights, in the county of Cook and 5 State of Illinois, have invented certain new and useful Improvements in Open-Slot Railway Crossings, of which the following is a specification.

This invention relates to railway crossings, 10 preferably made of manganese steel castings, and has for its object to provide a crossing structure which can be successfully produced by that method of manufacture, in a condition which will be particularly well adapted to withstand the very 15 severe stresses to which such a structure is subjected in use.

It has long been recognized that the interruption of the tread surfaces of each track 20 of a railway crossing, necessitated by the continuity of the flangeways of the intersecting track, causes very severe stresses to develop in the crossing member as a result of the hammering of the wheels against the 25 far sides of the intersecting flangeways. It has been proposed to insure the integrity of the crossing member under these stresses by making the casting exceedingly heavy, and it has also been proposed to minimize the 30 tendency to crack the casting on lines coinciding with flangeways, by increasing the depth of the flangeway sufficiently to insure a measure of resiliency in the walls which receive the hammer blows of the wheels.

35 The present invention proposes to meet the conditions by a novel construction of crossing member, the underlying feature of which consists in constructing the flangeways of a crossing member in the form of 40 open slots extending entirely through the casting in the vertical direction, and continuing longitudinally of each flangeway from the point of intersection of the flangeways such a distance as will permit the shock of 45 wheel hammer occurring at the intersection to be largely or wholly absorbed by the far side of the interrupted treadway, before it reaches the web or filling that defines the flangeway space at the outer end of the casting; an incidental feature of the invention, 50 however, consisting in reinforcing those portions of the castings which are separated by the flangeway slots through the medium

of suitable tension members, for instance, bolts bearing nuts, through which the bolts 55 may be placed under substantial loads of initial tension that will still further relieve the reduced connecting members at the outer ends of the casting, and, in fact, directly sustain the treadways themselves 60 under hammering shocks from the wheels. The bolts are preferably located at substantial angles to the walls of the intersecting flangeways, and therefore to the direction 65 of the shock to be withstood, and each sector of the casting which constitutes the crossing preferably receives a plurality of sustaining bolts; and in order that the bolts may be conveniently located in these positions, and their nuts seated normally to the direction 70 of the bolts, each crossing sector is formed with a diagonal wall constituting the base of a triangle of which the flangeway walls form the two sides. While the reduced web portions, which define the widths of the 75 flangeways at points remote from the intersection, are preferably formed integrally with the sectors of the casting, they may, in some instances, be in the nature of filler blocks held in place by transverse bolts, 80 and whether these slot-defining webs are integral or separately formed, such transverse bolts are preferably employed for the sake 85 of reinforcement.

In the accompanying drawing, in which 90 two embodiments of the invention are shown by way of illustration—

Figure 1 is a plan view of a cast metal railway crossing embodying the several features of the invention.

Figure 2 is a vertical section through one of the legs of the crossing, with parts beyond shown in elevation, the section being taken on the line 2^x—2^x of Figure 1.

Figure 3 is a view similar to Figure 2 but 95 showing a modification which consists primarily in the addition of a reinforce plate as a seating for the nuts on the diagonal bolts; and

Figure 4 is a vertical section of a fragmentary portion of the crossing, the section being taken on the line 4^x—4^x of Figure 1.

Referring to Figures 1 and 2, 1, 2, 3 and 4 represent sectors of a cast metal railway crossing adapted to serve as treadways or, alternately, as treadways and guard rails;

said sectors being separated by intersecting flangeways 5. According to the present invention, the flangeways 5 are constituted by slots extending entirely through the casting 5 in the vertical direction and continuing horizontally from the point of intersection X longitudinally of each flangeway to a point sufficiently remote from the said intersection to provide for absorption of a substantial portion, if not all, of the stresses which are set up in the members 1, 2, and 3 when, from the direction of movement of wheels, they happen to constitute the far side of the flangeway which divides them, and thus receive hammering shocks from the wheels. The through slots 5 are, in other words, terminated by spacing webs 5^a in the respective outer legs of the casting, which spacing members, while necessarily low enough beneath the upper surfaces of the casting to avoid interference with the flanges of the wheels, need have only such vertical dimension as will be necessary to resist the stresses imposed upon them; for instance, the vertical dimension illustrated at 5^a in Figures 2 and 3, thus leaving the vertical walls of the flangeways as resilient as practicable; and especially may the web members 5^a be thus vertically and longitudinally restricted in 30 dimension if the outer legs of the casting are reinforced by transverse bolts, such as shown at 6. With the presence of proper reinforcement, such as provided by bolts 6 and the diagonal reinforce bolts presently to be described, the web portions 5^a may even be reduced to a horizontal wall 5^b and a vertical wall 5^c, as shown in Figure 4, thus greatly reducing the thickness of metal and facilitating proper heat treatment of the 40 casting.

In order to reinforce the sectors 1, 2, 3 and 4, at points of greatest stress and throughout the slotted portions of the casting, diagonal bolts 7 are passed through the casting from each sector to a diagonally opposite sector, there being preferably, two bolts in each such relation, and the bolts are thus caused to assume positions at substantial angles to the flangeway slots 5 or the 50 walls of such slots that receive the wheel hammering. These diagonal bolts are, of course, in planes sufficiently below the tread surfaces to avoid interference with the wheel flanges. In order that said bolts may have a firm seating for their nuts, each sector of the casting is provided with a diagonal wall 8 related substantially as the base of a triangle, of which the flangeway walls of the particular sector constitute the sides, 55 said walls being substantially perpendicular to the direction of the bolts, and the bolts are seated against these walls through the medium of nuts 9 which adapt the bolts to be placed under initial stresses of tension and thus better adapt them to completely

resist loads imposed upon the sectors of the crossing.

In order that the sectors 1, 2, 3, and 4, as well as such portions of the outer legs of the casting as may involve increased thickness of metal, may be properly heat treated without impairing the substantially vertical support of the crossing member, said sectors or leg portions are of so-called solid tubular construction described in United States Letters Patent No. 1,460,107, of June 26, 1923; that is to say, said portions of the castings are essentially solid blocks of metal, so far as concerns the support which they afford to vertical loads, but they are so opened up by vertical bores or corings as to leave no portion of the metal of a greater thickness than that which can be properly tempered by the heat treatment which is common in manganese steel castings. And by way of carrying forward the idea of developing ample metal in the structure without defeating proper heat treatment, the diagonal walls 8, as illustrated in Figure 3, may be originally formed of channel section and provided with a filling or reinforce plate 8^a to receive the nuts 9 of the diagonal reinforce bars.

I claim:

1. A cast metal railway crossing, comprising intersecting treads and flangeways; a flangeway adjacent the point of intersection comprising a slot extending entirely through the casting.

2. A cast metal railway crossing, comprising intersecting treads and flangeways; a flangeway adjacent the point of intersection comprising a slot extending entirely through the casting but closed by a bottom web at a place remote from such intersection.

3. A cast metal railway crossing, comprising intersecting tread and guard portions with intervening flangeways; the flangeways at and adjacent the point of intersection comprising slots extending through the casting; and the treads and guards defining the slot-portions of the flangeways being constructed for independent vertical support.

4. A railway crossing member, comprising tread and guard sectors and intersecting flangeways, the flangeways comprising slots extending entirely through the casting.

5. A railway crossing structure, comprising tread and guard sectors separated by intersecting flangeways comprising slots extending vertically entirely through the casting; said flangeways being defined by spacing webs at points remote from their point of intersection.

6. A crossing structure, comprising tread and guard sectors, outer leg portions, intersecting flangeways extending vertically

entirely through the casting, and spacing webs within the portions of the flangeways lying in the outer leg portions; said outer leg portions being reinforced by transverse bolts.

5 7. A railway crossing, comprising tread and guard sectors separated by flangeway slots extending vertically through the casting, outer leg portions, and web portions limiting the depth of the flangeways in said outer leg portions; said web portions comprising horizontal walls having a thickness extending from the bottom of the flangeway but a portion of the distance toward the

10 undersurface of the leg portions, and vertical walls extending downwardly from said horizontal walls.

15 8. A railway crossing, comprising tread and guard sectors separated by flangeway slots extending vertically through the casting, outer leg portions, and web portions limiting the depth of the flangeways in said outer leg portions; said web portions comprising horizontal walls having a thickness extending from the bottom of the flangeway but a portion of the distance toward the undersurface of the leg portions, and vertical walls extending downwardly from

said horizontal walls; and said leg portions having transverse reinforce bolts.

30

9. In a railway crossing, comprising tread and guard sectors separated by vertical slot flangeways, and reinforcing bolts extending through and uniting diagonally opposite sectors of the crossing.

35

10. In a railway crossing structure, tread and guard sectors separated by vertical slot flangeways and having each a diagonal vertical base wall, and reinforce bolts extending through diagonally opposite sectors of the crossing and having seating members meeting said base walls.

40

11. In a railway crossing structure, tread and guard sectors separated by vertical slot flangeways and having each a diagonal vertical base wall, and reinforce bolts extending through diagonally opposite sectors of the crossing and having seating members meeting said base walls; said base walls being of channel section and having reinforce plates receiving the seating members of the bolts.

45

Signed at Chicago, Illinois, this 8th day of December, 1924.

WESLEY G. NICHOLS.
